CLAIM

The ornamental design for a holder with pads as shown and described.

DESCRIPTION

FIG. 1 is a front-right perspective view of a holder with pads according to the claimed design.

FIG. 2 is a rear-left perspective view of the holder with pads.

FIG. 3 is a top view of the holder with pads.

FIG. 4 is a bottom view of the holder with pads.

FIG. 5 is a front view of the holder with pads.

FIG. 6 is a rear view of the holder with pads.

FIG. 7 is a right side view of the holder with pads.

FIG. 8 is a left side view of the holder with pads; and,

FIG. 9 is a sectional view of the holder with pads taken along line 9-9 in FIG. 3.

1 Claim, 9 Drawing Sheets
